UNITED STATES PATENT OFFICE

136,479

DESIGN FOR A WELDING ELECTRODE HOLDER

Carl L. Wood, Richmond, Calif.

Application May 17, 1943, Serial No. 110,222

Term of patent 14 years

To all whom it may concern:

Be it known that I, Carl L. Wood, a citizen of the United States, residing at the city of Richmond, county of Contra Costa, and State of California, have invented a new, original, and ornamental Design for a Welding Electrode Holder, of which the following is a specification, reference being had to the accompanying drawing, forming part thereof.

Fig. 1 is a side elevation of a welding electrode holder showing my new design.

Fig. 2 is an elevational view of the open end of the welding electrode holder.

Fig. 3 is an elevational view of the closed end of the welding electrode holder.

I claim:

The ornamental design for a welding electrode holder, as shown.

CARL L. WOOD.
